UNITED STATES PATENT OFFICE

KARL H. ANDRÉN AND HAAKON T. OLSEN, OF MILWAUKEE, WISCONSIN, ASSIGNEES
TO ARTOS ENGINEERING COMPANY, OF MILWAUKEE, WISCONSIN, A CORPORATION
OF WISCONSIN

CUTTING MACHINE

Application filed June 27, 1925. Serial No. 39,933.

This invention relates in general to improvements in the art of subdividing materials into pieces of predetermined size, and relates more specifically to improvements in the construction and operation of machines for measuring, marking, scoring or cutting elongated material into portions of definite length, and to improved mechanism for feeding, conveying or transporting such materials.

A general object of the invention is to provide an improved machine for automatically measuring, marking, scoring or severing material into pieces of predetermined dimensions. Another general object of the invention is to provide improved mechanism for automatically transporting material to, through and from cutting machines or the like. A further general object of the invention is to provide simple and efficient knife structure for cutting machines, and improved mechanism for actuating the same.

Some of the more specific objects and advantages of the present improvement, are as follows:

To provide improved automatically operable cutting mechanism which is adapted to accurately cut material into pieces of predetermined size.

To provide a simple and efficient machine for cutting elongated or ribbon like material into pieces of any desired length.

To provide an improved guillotine cutter of maximum capacity and efficiency.

To provide improved mechanism for continuously delivering stock to a cutting or similar machine, and for either continuously or intermittently transporting the material through and from such a machine.

To provide improved stock feeding mechanism and cooperating marking or cutting structure, whereby minimum time is lost during the marking or cutting operation.

To provide improvements in feed and discharge mechanisms for cutting machines or

the like adapted to operate upon elongated material such as ribbon stock.

To provide improved driving mechanism for the cutters and the feed operating mechanisms of cutting machines or the like.

To provide simple and efficient means for releasing the cut stock from the blades of cutting or severing machines.

To provide improved automatic control mechanism for machines which are especially adapted to operate upon ribbon like stock.

To provide an improved and extremely effective knife action for the blades of cutting machines.

To provide simple and efficient means for maintaining uniform blade pressure between the knives of relatively large cutting machines.

To provide an improved cutting machine for severing material at any predetermined angle relatively to its surfaces.

To provide cutting mechanism and stock feeding means, all parts of which are readily accessible for inspection, adjustment and repairs.

To provide improved safety appliances especially applicable to measuring, marking, scoring or cutting machines.

To provide improvements in clutch mechanisms especially applicable to automatically functioning machines.

To provide various other improvements in the construction and operation of cutting and feeding mechanisms, whereby the cost of construction is reduced to a minimum and the efficiency is enhanced to a maximum.

These and other objects and advantages will be apparent from the following description.

A clear conception of embodiments of the various novel features of the invention and of the mode of operation of devices constructed in accordance therewith, may be had by referring to the drawings accompanying and forming a part of this specification in

which like reference characters designate the same or similar parts in the various views.

Fig. 1 is a part sectional side elevation of an improved guillotine cutter for elongated or ribbon like material, showing material supply and discharge conveyors associated therewith.

Fig. 2 is a front view of the improved cutting machine looking toward the knives thereof.

Fig. 3 is a full side elevation of the improved cutting machine viewed in a direction opposite to that of Fig. 1.

Fig. 4 is a part sectional front elevation of the improved cutting machine.

Fig. 5 is an enlarged fragmentary part sectional top view of the movable knife and its carrier, of the improved cutting machine.

Fig. 6 is an enlarged front view of the movable knife and its carrier, of the improved guillotine cutter.

Fig. 7 is an enlarged part sectional end view of the movable knife and its carrier.

Fig. 8 is an enlarged end elevation of the movable knife carrier.

Fig. 9 is an enlarged part sectional side view of the stationary knife and the improved mechanism for delivering the stock thereto and for releasing the cut stock therefrom.

Fig. 10 is an enlarged side view of the feed mechanism actuating crank.

Fig. 11 is an enlarged longitudinal section through the feed mechanism actuating crank showing the same associated with a fragment of the main gear segment.

Fig. 12 is an enlarged bottom view of the feed actuating crank showing the same associated with a fragment of the main gear segment.

Fig. 13 is an enlarged vertical sectional view through the feed belt actuating gearing and clutch.

Fig. 14 is an enlarged part sectional view showing details of the improved feeder actuating clutch.

Fig. 15 is an enlarged end elevation of one element of the improved knife actuating mechanism.

Fig. 16 is an enlarged top view of a fragment of the improved knife actuating mechanism.

Fig. 17 is an enlarged central vertical section through the improved knife actuating clutch mechanism.

Fig. 18 is an enlarged top view of one element of the improved knife actuating clutch mechanism.

Fig. 19 is an enlarged side elevation of the improved knife actuating mechanism.

While the various improvements are shown and described herein as having been specifically applied in a guillotine type of cutting machine, it will be apparent that many of the novel features are capable of more general application to other types of measuring,

marking, scoring and cutting machines. The guillotine cutter specifically illustrated, comprises in general mechanism for continuously supplying ribbon like stock 4 at a predetermined rate of speed and for intermittently advancing the stock through and delivering the cut material from the machine; relatively movable knives or blades 2, 3 for severing the stock 4 at an angle to its length into successive pieces of definite length; and gearing for operating the feed mechanism and the knives.

The mechanism for continuously supplying the stock 4 to the cutting machine, comprises a movable conveyor belt 6 having its delivery end spaced from the rear of the machine proper as shown in Fig. 1, the belt 6 being operable to deliver the ribbon stock 33 into the said space as shown.

The mechanism for intermittently feeding or transporting the stock 4 toward and past the blades 2, 3, comprises an endless feed belt 5 coacting with pulleys 26, 27, 28, and a series of parallel feed rollers 30 rotatably supported in side frames 25 which are pivotally suspended from a cross shaft 53.

The upper stretch of the feed belt 5 and the horizontal rollers 30 cooperate to provide a downwardly and forwardly inclined runway for the stock 4 which is intermittently withdrawn from the space between the supply belt 6 and the cutting machine.

The mechanism for either intermittently or continuously delivering the cut stock from the machine, comprises a movable conveyor belt 7 the receiving end of which is disposed underneath the knife blades 2, 3 as shown in Fig. 1, and which is supported by a positively rotated actuating roller 24.

With the supply and feed belts 6, 5 disposed as shown and described, the uncut continuous ribbon 33 sags during the cutting operation, while the excess material is intermittently removed during the feeding operation to reduce the extent of sagging as indicated by the dot and dash line in Fig. 1.

For the purpose of effecting automatic control of the operation of the cutting machine, limit switches 89, 90 may be disposed above and below the sagging ribbon 33, these switches being operable to slow down the actuating motor in case the upper switch 89 is operated by insufficient sagging of the ribbon 33, and to speed up the motor in case the lower switch 90 is operated by excessive sagging of the stock.

The main frame of the cutting machine comprises a pair of side frames 29 supported upon a base 49 and interconnected at their upper ends by one or more tie rods 47, an auxiliary end frame, and a pair of compression members 100.

The main frame besides providing a support for the stock feeding mechanism, also constitutes a support for the stationary knife carrier 16 and provides upright guideways 20 for the movable knife 3. The

movable knife carrier 19 is vertically reciprocable within the guideways 20 and has a knife support 21 suspended therein at a slight angle relatively to the plane of the cutting edge of the stationary blade 2 as shown in Fig. 5, by means of horizontal pivots 37. The cooperation of the blades 2, 3 is such that the cutting edges have point contact only, the movable knife being urged toward the stationary blade 2 by means of a compression spring 34 coacting with the blade support 21 and with an adjustable cap 52. The movable blade 3 is properly positioned relatively to the stationary blade 2 by means of a nut 35 cooperating with the carrier 19 and with a stud associated with the carrier 21. A roller 22 associated with the movable knife carrier 21 coacts with a resiliently retained rail 23 the upper end of which is pivotally associated with one of the side frames 29, and the lower extremity of which reacts against a compression spring 69 associated with a tension rod 68 as shown in Fig. 3. The tension of the spring 69 is adjustable to produce a desired uniform pressure upon the movable blade 3 throughout the entire cut. The movable blade carrier 21 is further provided with a downwardly projecting knife guide 36 for positively preventing this blade from moving downwardly along the rear side of the stationary blade and for maintaining the movable blade 3 in front of the stationary blade 2 at all times.

The opposite ends of the knife carrier or support 19 are provided with outwardly extending actuating pins 38 which are engaged by the upper extremities of the adjustable knife actuating connections 39 the lower extremities of which engage the crank pins 51. The crank pins 51 are carried by cranks 50 secured to the opposite ends of the knife actuating shaft 9 which is supported in the side frames 29. The shaft 9 is intermittently rotatable to vertically reciprocate the movable knife 3, by means of clutch mechanism shown in Figs. 15, 16, 17, 18 and 19. The knife actuating clutch comprises a member 40 keyed to the shaft 9 and having an annular groove 41 therein within which a block 42 carried by an end of the lever 43 is adapted to ride. A latch bar 79 having a wedge surface 82 is carried in a transverse opening in the member 40, the bar 79 being urged toward the right as viewed in Fig. 17 by means of a spring 81. The spur gear 54 is loosely mounted upon the shaft 9 and has a pair of hardened wearing pins 80 extending transversely therethrough, the pins 80 being cut away to provide a slot 83 adapted to receive the end of the latch bar 79. The gear 54 is continuously rotatable by means of a gear 85 secured to the power shaft 8 which also carries a gear 55 meshing with a pinion 86 secured to the main driving shaft 88, the shaft 88 being continuously rotatable by means of a driving motor or pulley 46. The medial portion of the clutch actuating lever 43 is pivotally associated with the shaft 8 while the rear end thereof carries a roller 44 which is cooperable with a cam 45 secured to a continuously rotatable cross-shaft 10. The lever 43 is movable in a counter-clockwise direction about the shaft 8 by means of a spring 84 the lower end of which is attached to the base 49, and is intermittently movable in the opposite direction by the rotating cam 45.

The shaft 10 is supported in bearings in the side frames 29 and is continuously rotatable by means of intermeshing gears 56, 57, 59, the gear 56 being secured to the power shaft 8, the gear 59 being secured to the shaft 10, and the gear 57 being carried by an intermediate idler shaft. The feed belt actuating crank 48 is secured to an end of the shaft 10 and carries a cross-head 32 which is adjustable along the crank 48 by means of a threaded rod 64 to vary the rate of feed, see Figs. 3, 4, 10, 11 and 12. The cross-head 32 coacts with a slot in a gear segment 17 which is oscillatably supported upon a pivot 18 associated with one of the side frames 29, and meshes with a pinion 60 secured to one end of a counter shaft 11. The counter shaft 11 also carries a collar 77 to which a gear 61 is drivingly connected by means of one or more shear pins 78 as shown in Fig. 13. The gear 61 meshes with a pinion 62 which is rotatably supported upon the feed belt driving shaft 53 to which the driving drum 26 is secured. The pinion 62 has a lateral projection 72 which is drivingly connected to an internal clutch member 73 having a plurality of inclined or wedge surfaces 76 coacting with locking rollers 74 as shown in Figs. 13 and 14. The rollers 74 also coact with the interior surface of an outer clutch member 63, and are urged along the wedge surfaces 76 by means of helical compression springs 75 which react against projections on the internal clutch member 73. The outer clutch member 63 is keyed to shaft 53 and is positively prevented from rotating in a counter-clockwise direction as viewed in Fig. 14, by means of a locking roller 70 coacting with the periphery of the member 63 and with an inclined stationary abutment 71 formed integral with the adjacent side frame 29.

The medial portion of the shaft 10 carries a continuously rotatable cam 12 formed for intermittent coaction with a roller 13 carried by the lower end of a feed roller shifting lever 14, see Figs. 4 and 9. The lever 14 is clamped to the medial portion of a pivot 31 the ends of which are rigidly attached to the feed roll supporting frames 25 in which the feed rolls 30 are rotatably supported. The rolls 30, frames 25, pivot 31 and lever 14 are simultaneously movable about the cross-shaft 53 in a clockwise direction as viewed

in Fig. 9, by the cam 12 and are automatically returnable to the position indicated in Fig. 9, by gravity, when the cam 12 becomes ineffective. The counter-clockwise movement of the feed rolls 30 is limited by a stop rod 15 secured to the stationary knife carrier 16 and loosely penetrating a lug 65 formed integral with the lever 14. The roller supporting frames 25 provide bearings for a cross-shaft 58 to which a gear 66 is secured. The gear 66 meshes with a gear 87 secured to the feed belt driving shaft 53 and also meshes with pinions secured to the ends of the two upper feed rolls 30 so as to positively rotate these rolls. The two lower feed rolls 30 are positively rotated by means of a chain 91 coacting with sprockets at the corresponding ends of the three lowest rolls 30. The cross-shaft 53 is connected by means of a chain drive 67, to the discharge conveyor driving drum 24, as shown in Fig. 1 to impart motion to the conveyor 7 simultaneously with the rolls 30, but the conveyor 7 may obviously be otherwise driven.

During normal operation of the improved cutting machine, the various mechanisms are set in motion by means of power applied to the pulley 46 secured to the driving shaft 88. Rotary motion of the shaft 88 is transmitted through the pinion 86 and the gear 55 to the power shaft 8, and from thence through the pinion 56 and gear 85 to the shafts 10, 9 respectively, thereby causing the gear 54 and shaft 10 to rotate continuously. The continuously rotating shaft 10 carries with it the cams 12, 45 and the crank 48 which automatically actuate the material releasing roll 30, the movable knife blade 3 and the feed belt 5 at predetermined intervals.

With a ribbon of stock 4 disposed upon the continuous supply and intermittent feed mechanisms as shown in Fig. 1, and assuming that the movable knife 3 has just completed a cut, the knife actuating cam 45 is in engagement with the roller 44 and holds the block 42 out of the slot 41 of the clutch element 40. The locking pin 79 is then free to move and is held within the slot 83 of the continuously rotating gear 54 by virtue of the pressure produced upon the pin by the spring 81. With the elements thus disposed, the shaft 9 is drivingly connected to the gear 54 and remains thus connected until the knife 3 has been fully elevated and the gap between the blades 2, 3 is open. When the blades 2, 3 have been fully separated, the cam 45 disengages the roller 44 and the spring 84 becomes effective to return the block 42 into the groove 41. As the clutch element 40 continues to rotate, the chamfered nose of the block 42 rides along the wedge surface 82 and withdraws the pin 79 from the slot 83 thereby releasing the knife driving connection and stopping the blade 3 in elevated position.

After the movable blade 3 has been sufficiently elevated, the cam 12 on the rotating shaft 10 engages the roller 13 of the lever 14 and automatically swings the side frames 25 and the feed rolls 30 associated therewith, about the shaft 53 as a pivot, in a clockwise direction as viewed in Fig. 9. The upward or lateral movement of the feed rolls 30 effectively releases the severed end of the stock 4 from the stationary blade 2 and permits subsequent free delivery of the ribbon of stock through the gap between the blades 2, 3. Immediately after elevation of the feed rolls 30, the rotating crank 48 at the end of the shaft 10 becomes effective to swing the gear segment 17 in a clockwise direction as viewed in Fig. 3, thereby producing rotation of the inner clutch member 73 in a similar direction and causing the clutch rollers 74 to ride along the wedge surfaces 76. As the clutch rollers 74 become jammed between the wedge surfaces 76 and the inner surface of the outer clutch member 63, the outer member is also positively rotated and produces rotation of the shaft 53 and of the feed belt driving drum 26. The rotary motion of the shaft 53 is transmitted to the feed rolls 30 and the rotating drum 26 advances the upper stretch of the feed belt 5, the rolls 30 and the belt 5 cooperating with each other to quickly advance the stock 4 through the gap between the separated knife blades 2, 3 and upon the conveyor 7 which is advancing simultaneously with the movement of the rolls 30 and of the belt 5. The cam 12 on the rotating shaft 10 eventually becomes ineffective and releases the roller 13, whereupon the feed rolls 30 and the elements associated therewith drop by gravity and bring the advanced stock 4 into substantial engagement with the stationary blade 2. The downward movement of the rolls 30 is checked by engagement of the lug 65 with the nut at the end of the rod 15.

When the segment 17 has been swung forward to its extreme position as determined by adjustment of the cross-head 32, continued rotation of the shaft 10 and of the crank 48 produces reverse oscillation of the segment 17 about its pivot 18. Such reversal of the movement of the segment 17 immediately causes automatic release of the driving connection between the outer and inner clutch elements 63, 73, and the locking roller 70 quickly becomes effective to stop and to prevent reverse rotation of the shaft 53 and to lock the feed belt 5, the rolls 30 and the discharge belt 7 against movement. Simultaneously with the reversal of movement of the segment 17, the knife actuating cam 45 again becomes effective to engage the roller 44 and to swing the lever 43 in a clockwise direction as viewed in Fig. 19, thereby automatically removing the block 42 from the groove 41 and again connecting the shaft 9

with the power. The blade 3 is thereupon moved downwardly and cooperates with the stationary blade 2 to sever the stock 4 at an oblique angle relatively to its length. Upon continued application of the power, the foregoing cycle of operations is repeated and successive pieces of material of definite length are severed from the ribbon 4 and are discharged by the conveyor 7.

While the cutting machine is thus functioning to alternately advance the material and sever it into successive pieces of predetermined length, the supply conveyor 6 is continuously delivering new stock into the gap between the delivery end of the conveyor 6 and the cutting machine. The excess stock 33 thus delivered into this space, sags as shown in Fig. 1 and is intermittently elevated to the dot and dash line position during forward feeding by virtue of the relatively high speed operation of the feed belt 5. When it is desired to effect automatic control of the machine, the limit switches 89, 90 cooperating with a suitable driving motor, may be employed. With the aid of these switches, it will be apparent that if the stock 4 is delivered from the conveyor 6 into the space at the delivery end thereof at too rapid a rate, the excess stock will engage and automatically operate the lower switch 90 to speed up the operation of the cutting machine and to thereby eliminate excess sagging. If the stock 4 is delivered from the supply conveyor 6 too slowly, the ribbon 33 will eventually engage and operate the upper switch 89 to slow down the operation of the cutting machine.

From the foregoing description it will be obvious that the improved machine functions to automatically and effectively cut the continuous ribbon of stock 4 into successive pieces of equal and predetermined definite length. The relative disposition of the actuating shaft 10 and of the segment 17 is such that the feeding period is considerably longer than the cutting period, thereby enabling extremely rapid operation of the machine with minimum loss of time during cutting. As specifically illustrated, the cutting operation consumes about one half of the time utilized during the feeding operation, but this relationship between these periods may obviously be varied. By changing the position of the cross-head 32 relatively to the crank 48, the length of the successive pieces cut may be readily varied, and all pieces cut with a predetermined setting of the cross-head 32 are exactly equal in length. The various mechanisms function automatically to perform their several duties, and the time of each operation may be readily varied by adjustment to produce maximum efficiency of operation. The knife and the feed mechanism actuating clutches are rapid, positive and extremely efficient in operation, the

springs 75 cooperating with the rollers 74 of the latter clutch to insure extremely rapid functioning of this device. The laterally shiftable feed rolls 30 automatically remove sticky stock 4 from the stationary blade 2 after cutting, and facilitate subsequent advancement of the stock between the knife blades 2, 3. By locating the receiving end of the discharge conveyor 7 below the stationary knife support 16, delivery of the stock 4 to the conveyor 7 is also facilitated, especially when operating upon gummy stock. The compression members 100 absorb the entire cutting pressure and relieve the main side frames from excessive stresses by virtue of the mounting of the carrier 16 and of the shaft 9 at opposite ends thereof.

The improved knife action embodied in this machine also insures clean cutting of any kind of material, including relatively soft and sticky tire stock. It should be noted that by pivotally suspending the vertically movable knife blade 3, by disposing this blade at an angle to the plane of the cut, and by providing relatively inclined cutting blade edges, the blades 2, 3 have point contact only with each other and substantially constant cutting angle between the cutting edges is maintained throughout the cut. The pressure of coaction between the blades 2, 3 may be conveniently adjusted by adjusting the spring 69, and this spring automatically maintains constant pressure of coaction between the cutting edges. The guiding projection 36 effectively prevents overlapping of the blades 2, 3 and insures proper cooperation of the cutting edges.

The entire structure is relatively simple, compact and highly efficient considering the work which it performs, and all portions thereof are readily accessible for inspection, adjustment and repairs. While the novel features are shown and described as being specifically applied to a guillotine type of cutting machine, it will be apparent that at least some of these features are capable of advantageous general application to other types of measuring, marking, scoring or cutting machines.

It should be generally understood that it is not desired to limit the invention to the exact details of construction and operation herein specifically shown and described, for various modifications within the scope of the claims may occur to persons skilled in the art.

It is claimed and desired to secure by Letters Patent:—

1. In combination, a knife movable in a plane, a series of rollers formed to deliver material toward the plane of movement of said knife, and means for periodically moving said rollers transversely of their axes to permit the same to project material across said plane.

2. In combination, a knife movable in a plane, a series of substantially parallel roll-

- ers formed to deliver material toward the plane of movement of said knife at an oblique angle, and means for periodically simultaneously moving said rollers transversely of their axes to permit the same to project material across said plane.
3. In combination, a knife movable in a plane, a series of rollers formed to deliver material toward the plane of movement of said knife, means for simultaneously positively rotating all of said rollers in the same direction, and means for periodically moving said rollers transversely of their axes to permit the same to project material across said plane.
4. In combination, a knife movable in a plane, a series of rollers formed to deliver material toward the plane of movement of said knife at an oblique angle, an endless band conveyor formed to deliver material upon said rollers and toward said plane, and means for moving said rollers transversely of their axes to change the direction of delivery of the material relative to said plane.
5. In combination, means for cutting material into predetermined lengths, a plurality of rolls for delivering material toward said cutting means, means for rotating said rolls about their own axes, means for moving said rolls transversely of said axes to change the direction of delivery of the material relative to said cutting means, and means for intermittently delivering uncut material to said rolls.
6. In combination, a knife having a cutting edge, a roller located closely adjacent to said edge for feeding material to said knife, means for periodically moving said roller transversely of its axis to release material from said edge, and means for positively rotating said roller to project material over said edge.
7. In combination, a fixed blade, a movable blade, said blades having relatively inclined cutting edges and the cutting edge of one of said blades being disposed at an angle relative to the plane of cutting, a support for said movable blade, means for moving said support to cause the edges of said blades to operate, and a spring reacting against said support for resiliently urging the edges of said blades against each other.
8. In combination, a fixed blade, a movable blade, said blades having relatively inclined cutting edges and the cutting edge of said movable blade being disposed at an angle to the plane of cutting, a support movable relatively to said fixed blade, means for pivotally suspending said movable blade from said support, and means reacting against said support for resiliently urging the edges of said blades against each other.
9. In combination, a knife movable in a vertical plane, means for advancing material downwardly at an oblique angle relatively to said plane, and a discharge conveyor crossing said plane and disposed beneath said knife and said advancing means.
10. In combination, a stationary knife, a movable knife cooperable with said stationary knife to cut material, a roller carried by said movable knife, and a resiliently retained rail cooperating with said roller during relative movement of said knives.
11. In combination, a knife movable in a plane, rotary means for delivering material toward the plane of movement of said knife at an oblique angle, an endless band conveyor formed to deliver material upon said rotary means and toward said plane, and means for moving said rotary means transversely of the axis of rotation to change the direction of delivery of the material relative to said plane.
12. In combination, a knife, rotary means for delivering material toward said knife, means for moving said rotary means transversely of the axis of rotation to change the direction of delivery of the material relative to said knife, and means for intermittently delivering uncut material to said rotary means.
13. In combination, a knife movable in a vertical plane, a series of rollers for advancing material downwardly at an oblique angle relatively to said plane, and a discharge conveyor crossing said plane and extending beneath said knife and said advancing means.
14. In combination, a knife movable in a vertical plane, means for advancing material downwardly at an acute angle toward said plane adjacent to said knife, and a discharge conveyor crossing said plane and extending beneath said knife and said advancing means.
15. In combination, a knife having a cutting edge movable in a substantially vertical plane while cutting, means for advancing material downwardly and toward said plane at an acute angle, and means for elevating said advancing means to project material across said plane when said knife is open.
16. In combination, a knife operable to cut material in a substantially vertical plane, means for holding material at an acute angle relative to said plane during cutting, and means for moving the severed end of the advancing stock away from a cutting edge of said knife before projecting said material across said plane preparatory to subsequent cutting.
17. In combination, a knife having cutting edges relatively movable in a substantially vertical plane to cut material, means for feeding material downwardly and toward said plane at an acute angle, and means for moving the severed end of said material away from a cutting edge of said knife before projecting said end across said plane between said edges preparatory to subsequent cutting.

18. In combination, a knife operable to cut material in a substantially vertical plane, and a series of rollers for supporting material directed downwardly at an acute angle relative to said plane during cutting and for subsequently feeding the severed end of said material across said plane.

In testimony wheréof, the signatures of the inventors are affixed hereto.
